US0D1107910S

(12) **United States Design Patent** (10) **Patent No.:** **US D1,107,910 S**
(45) **Date of Patent:** **** Dec. 30, 2025**

(54) **CATHETER INTERFACE**

(71) Applicant: **KONINKLIJKE PHILIPS N.V.**,
Eindhoven (NL)

(72) Inventors: **Volker Barnhart Verschoor**,
Eindhoven (NL); **Aydin Mert**,
Eindhoven (NL); **Franciscus Reiner**
Antonius Van Der Linde, Schijndel
(NL); **Adrianus Johannes Josephus**
Van Der Horst, Vught (NL)

(73) Assignee: **KONINKLIJKE PHILIPS N.V.**,
Eindhoven (NL)

(**) Term: **15 Years**

(21) Appl. No.: **29/943,236**

(22) Filed: **May 21, 2024**

(57) **CLAIM**

The ornamental design for a catheter interface, as shown and described.

DESCRIPTION

FIG. 1 is a perspective view showing a catheter interface of our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

(Continued)

The portions of the catheter interface shown in broken lines are included for the purpose of illustrating unclaimed portions of the catheter interface and form no part of the claimed design.

1 Claim, 2 Drawing Sheets
